UNITED STATES PATENT OFFICE.

VICENTE FONT, OF HABANA, CUBA.

FLOOR AND ROOF CONSTRUCTION.

1,073,972.

Specification of Letters Patent. Patented Sept. 23, 1913.

Application filed May 6, 1911. Serial No. 625,504.

To all whom it may concern:

Be it known that I, VICENTE FONT, a citizen of the Republic of Cuba, residing at Calle B No. 74, Vedado, Habana, Cuba, have invented new and useful Improvements in Floor and Roof Constructions, of which the following is a specification.

This invention relates to building construction and more particularly to the combination of members arranged to resist the transverse stresses liable to be subjected thereto, such as floor and roof constructions.

It comprises a plurality of suitably supported members spaced apart from each other, such as I beams or built up girders, and a plurality of spanning members adapted for support by such members, and so constructed as to transmit the loads coming thereupon to the supports, the disposition of the parts being such that they may be wholly or partly covered by fire resisting material, such as concrete, where such is desirable.

The objects of my invention are to provide such a construction which is light, durable and easily assembled, with the parts disposed to form a rigid construction and thus serve as a wind brace to the structure as well as a construction free from vibration. I attain these objects by the construction and the arrangement of parts illustrated in the accompanying drawings, in which,—

Figure 1 is a sectional view through a floor construction taken longitudinally with the spanning members; Fig. 2 is a plan view of a portion of floor construction, parts being broken away to show the relation of the members one to another; Fig. 3 is a perspective view showing one of the spanning members supported by an I beam; Fig. 4 is a central transverse section through one of the spanning members; Fig. 5 is a side elevation of one of the spanning members showing its relation to the supporting I beam, and Fig. 6 is a sectional view taken substantially at the neutral axis of one of the spanning members.

In the drawings, 1 represents an I beam having the usual web 10, compression flange 8 and tension flange 14. Adapted for support by the I beams are spanning members 2 made up of various concrete compositions, terra cotta or the like, each having a central longitudinal web 5, a compression flange 6 and a tension flange 7. It is also desirable

that, especially in the case of relatively long spanning members that such be provided with central transverse bracket-like webs 16 under the upper flanges 6.

As shown in the drawings, spanning members 2 may be provided with reinforcing suspension means such as the tension rod 17, embedded in the tension flange 7 and looped into, and extending from the compression flange 6.

In order to form supporting means for the spanning members, the compression and tension flanges of their respective members merge into one another at preferably the neutral axis of the member, forming outstanding portion for engagement with the flanges 14, and are preferably formed at each end with an inclined face 4, a vertical face 3, a bearing face 11 and an inclined wedge face 12.

In order to assemble the spanning members between the supports 1, the spanning members are relatively reduced in length so that, when in place, a space 13 is left between the vertical face 3 and the web 10 of the I beam. This space 13 allows for expansion and contraction of the spanning members.

With reference to Fig. 1 of the drawing, the I beam is shown surrounded by a wedge shaped filling 9 of fire resisting material, such as cinder concrete, which is leveled off as at 18 to the floor level, the space under the tension flange of the I beam being protected by a wedge-shaped formation of cement-like material 15, which is held in place, when set, by the inclined faces 12 of the spanning members. The wedge shaped filling 9 embeds the extending portions of reinforcing rods 17 and, should the outstanding portions formed at the juncture of the upper and lower flanges become ruptured, the structure will remain stable through the wedging position of the filling 9 adjacent the ends of the spanning members.

From the foregoing description it is made manifest that I provide an economical and substantial floor and roof construction, the spanning members of which, owing to their relatively reduced length with respect to the spacing of the supporting member, are readily assembled in place as shown in Fig. 3.

I claim:—

In floor and roof construction, the combination of I-shaped supporting beams

spaced apart from each other, an I-shaped spanning member having the upper flange inclined downwardly at each end thereof to merge into the end face of said member at 5 the neutral axis thereof, and having its opposite ends forming outstanding portions which are supported upon the lower flanges of said beams, said spanning member being relatively reduced in length with respect 10 to the spacing of the supporting beams so as to leave spaces between the end faces of said outstanding portions and the webs of said supporting beams, reinforcing suspension means embedded in the lower flange of 15 said spanning member and alined with the

central longitudinal web thereof and extending from and beyond the said inclined portions of said upper flanges, and wedge shaped fillings between the webs of said beams and said inclined portions of said 20 upper flanges and embedding the extending ends of the reinforcing suspension means, substantially as and for the purpose set forth.

In testimony whereof I have affixed my 25 signature in presence of two witnesses.

VICENTE FONT.
